UNITED STATES PATENT OFFICE

2,400,621

TREATMENT OF HYDROCARBON GASES

Joseph G. Alther, Chicago, Ill., assignor to Universal Oil Products Company, Chicago, Ill., a corporation of Delaware

Application June 17, 1939, Serial No. 279,668, which is a continuation of application Serial No. 16,309, April 15, 1935. Divided and this application July 28, 1941, Serial No. 404,273

3 Claims. (Cl. 260—683.15)

The invention relates particularly to the treatment of hydrocarbon gases produced in connection with the refining of crude petroleums, with the object of producing gasoline fractions therefrom. This application is a division of my co-pending application, Serial No. 279,668, filed June 17, 1939 which, in turn, is a continuation of my earlier application, Serial No. 16,309, filed April 15, 1935.

In a more specific sense the invention is concerned with the conversion of selected and limited fractions of such gases by a series of cooperative steps involving catalytic treatment and fractionation. The process is particularly applicable to the treatment of so-called "propane-butane fractions" produced in the cracking of heavier and less valuable portions of petroleums with the object of producing gasoline.

The term "propane-butane fraction" refers to a particular group of hydrocarbons of restricted boiling range including principally the paraffin hydrocarbons, propane and the butanes and includes the corresponding olefins of the same number of carbon atoms, that is, propylene and butylenes. The present process is a contribution to processes aimed at the more efficient utilization of the propane-butane fractions as defined above, and the features and advantages of the process will be disclosed in the following specification.

In one specific embodiment the present invention comprises the polymerization of propane-butane fractions containing high percentages of readily polymerized olefins by contact with solid phosphoric acid catalysts, fractionation of the resulting products to produce fixed gases, intermediate fractions comprising essentially unconverted propane and butanes and the corresponding olefin hydrocarbons, comprising unpolymerized propylene and butylenes which are returned for further polymerization, and gasoline boiling range liquid polymer fractions.

According to the present invention the propane-butane fraction is defined as the intermediate hydrocarbon fraction produced either from gases or from the stabilization of low boiling gasolines which contain principally propane and the butanes and material percentages of propylene and the butylenes and also minor amounts of hydrocarbons of less than three carbon atoms comprising ethane, ethylene and methane and also the vapors of pentanes and amylanes.

The steps of the present process whereby hydrocarbon mixtures comprising essentially those of 3 and 4 carbon atoms are converted into gasoline boiling range fractions of superior antiknock

value may be conveniently described in connection with the attached drawing which shows diagrammatically in side elevation a plant hookup embodying the necessary interconnected units for accomplishing the objects of the invention. The drawing will be used to describe a typical process flow but the scope of the invention is not limited in exact correspondence therewith since the relative sizes of units may be varied considerably from the proportions shown in the drawing and since minor alterations in the flows and also such items as heat exchange may be introduced as found desirable or necessary.

Referring to the drawing, a propane-butane fraction with considerable percentages of propylene, butylenes, and amylanes is passed through line 20 containing control valve 21 through a heating element 22 in furnace 23 to be brought up to the temperature and pressure requisite to the efficient polymerization in the succeeding stage of the process. These temperatures will commonly be comprised within the range of 250 to 550° F., and the pressures may be varied over a wide range since pressure apparently has no independent effect upon the polymerization reactions, although ordinarily pressures of about 100 to 300 pounds per square inch are used. The heated vapors of the intermediate fraction then pass through line 24 containing control valve 25 and are subjected to the action of selected polymerizing catalysts in a series of towers 26, 29, and 32. The character of the catalyst which it is preferred to use at this point is unique and it will be in point to devote some space to its description.

In general the catalysts employed may be designated as "solid phosphoric acid" catalysts. These are prepared by initially incorporating phosphoric acids (preferably the ortho or the pyro acid) with relatively inert and usually siliceous absorbent carrying and spacing materials, heating the pasty mass until a solid cake is obtained and then grinding the cake to produce granular particles for tower filler. It is a feature of the catalysts prepared in this manner that for most purposes the active acid constituent constitutes the major portion by weight of their weight. Thus the final catalyst granules may show as high as 70% by weight of phosphoric acid and it is common practice to employ mixes comprising 60% of acid approaching the pyro acid in composition and 40% of carrier. However, in the case of gas mixtures which contain very high percentages of easily polymerized ole-

fins, the percentage by weight of active acid may be reduced even as low as 30%.

The carrying materials which are preferably employed in the manufacture of solid phosphoric acid catalysts include such materials as diatomaceous or infusorial earths, artificially precipitated forms of silica, and aluminum silicates such as, for example, bentonites and montmorillonites representing members of the kaolin division of clay minerals. The diatomaceous earths are particularly suitable for this service.

In preparing the catalysts it is essential that the primary mixes of carrier and acid be heated to temperatures within the approximate range of 480-570° F., to produce by dehydration the acid composition corresponding to maximum catalyzing effectiveness. The acid composition corresponds apparently to a ratio of phosphorus pentoxide to water slightly higher than that of pyrophosphoric acid, but owing to the difficulties of analysis, the presence of minor amounts of silicophosphoric acid complexes and the difficulty of differentiating between combined and adsorbed water, it is not possible to completely identify the acid and reliance is therefore placed upon standardizing the method of preparation. Advantages are sometimes gained by initially overheating and consequently over-dehydrating the absorbed acid and then subsequently rehydrating with steam, as this apparently increases the porosity of the granules and hence their active surface.

The preferred type of contact polymerizing material gradually becomes fouled by deposition of heavy polymers and carbonaceous material but is readily regenerated at such times by air oxidation followed by rehydration with steam if necessary.

The polymerizing units have been shown in the drawing in series connection with the olefin containing gases from the first stage passing downwardly through catalyst beds in succession. The towers may also be connected in parallel to permit the alternate use and regeneration of their contained material. Furthermore, the drawing shows no provision for the removal of liquids which may separate at the temperature of operation of the towers and in some instances wherein a large amount of normally liquid materials is produced in the primary treating towers it may be best to remove condensates and prevent their further contact with catalyst, thus avoiding over-polymerization with the development of high boiling polymers and also preventing the wetting and contaminating of the succeeding catalyst bed.

As shown in the drawing the heated gas mixtures from furnace 23 pass through line 24 containing control valve 25 downwardly through polymerizing tower 26, thence through line 27 containing control valve 28, and downwardly through tower 29 and from there through line 30 containing control valve 31 through tower 32. Following the polymerizing step the total products then follow line 33 containing control valve 34 to a cooler 35 which is operated at the best temperature for enabling good separation of fixed gases and the cooled and partly liquefied entering products leave the coil through line 36 containing control valve 37 to enter separator 38 from which the fixed gases are released through line 39 containing control valve 40.

If desirable for any reason, a portion of the fixed gases at this point may be directed for recycling by way of branch line 41 containing con-

trol valve 42 to mix with the gases from the final stabilizer. The liquids in separator 38 will now comprise polymers of substantially gasoline boiling range plus dissolved propane and butanes 5 and some dissolved propylene and butylenes. The products are now finally stabilized to produce a liquid polymer fraction of proper vapor pressure and an overhead comprising recycle stock and composed principally of 3 and 4 carbon atom hydrocarbons. As before, stabilizer 45 which receives charge from line 43 containing control valve 44 may include the usual reboiling coils and provision for recirculating a portion of the overhead to control the distillation.

The overhead from stabilizer 45 passes through line 39' containing control valve 40' and flows through the extension of line 41 through condenser 46 which is operated under sufficiently low temperature to condense the light recycle stock 20 which passes through line 47 containing control valve 48 to an intermediate accumulator 49 having a conventional gas release line 50 containing control valve 51 and a line 52 containing control valve 53 and leading to recycle pump 54. By reason 25 of the polymerization, the recycle stock collected in accumulator 49 is leaner than the charging stock with respect to higher olefins, that is, propylene and butylenes.

From this point the recycle stock may be returned to different points in the process for further treatment. By following line 55 containing control valve 56 it may be separately reheated in tubular heating element 57 arranged in furnace 58 after which the heated products may 30 pass through line 61 containing control valve 62 to the entrance to the catalytic polymerizing units. The temperatures and pressures for heating the recycle gases may thus be independently controlled so that the net effect on the quality and quantity of the final product is at an optimum.

If desired, the recycle stock may be passed by way of line 63 containing control valve 64 to the entrance of heater 22 to be raised in temperature 45 along with the charge introduced through line 20. The return of the recycle stock serves to maintain a predetermined concentration of higher olefins (propylene and butylenes) in the catalytic polymerizing operation.

Liquid polymers constituting the major portion of the product of the process leave the bottom of stabilizer 45 through line 70 containing control valve 71 and pass through a cooler 72 after which they flow through line 73 containing control valve 74 to enter storage.

It will be evident from the preceding description that, while the characteristic features of the process are sufficient to define it, it possesses considerable flexibility in the polymerizing step and 60 the recycling features. Owing to the general flexibility the process is capable of producing somewhat variable results both as regards yield and quality of product. However, the following is selected from the available examples to indicate 65 the general character of the results obtainable.

A propane-butane fraction subjected to polymerization had approximately 30% of olefins including propylene and higher and gave a yield of approximately 5 gallons of gasoline boiling range liquids for 1000 cubic feet of the gas admitted to the polymerizing plant.

It will be evident from the foregoing specification and example of the results obtained by the use of the process, that it is an improvement over similar processes in its field, but at the same

time neither are to be construed in the light of imposing limitations upon the broad scope of the invention.

I claim as my invention:

1. In the production of polymerized olefins wherein a heated gaseous mixture containing a substantial amount of normally gaseous higher olefins is passed at a temperature not substantially in excess of about 550° F. in contact with a catalyst, the product of the catalyzing operation 10 is subjected to a stabilizing operation to form a liquid product and a composite normally gaseous product lean with respect to its content of higher olefins, the improvement which comprises returning at least a portion consisting of a controlled quantity of said composite lean gaseous product to the catalyzing operation, whereby a predetermined concentration of higher olefins is maintained in the catalyzing operation.

2. In the production of polymerized olefins wherein a heated gaseous mixture containing a substantial amount of normally gaseous higher olefins is passed at a temperature not substantially in excess of about 550° F. in contact with a catalyst and the product resulting from the catalyzing operation is subjected to fractional separation in a stabilizing chamber to form a liquid product and a composite normally gaseous product lean with respect to its content of higher

olefins, the improvement which comprises withdrawing at least a portion consisting of a controlled quantity of the composite lean gaseous product of the stabilizing operation, and introducing said portion into the catalyzing operation together with fresh heated gaseous mixture containing a substantial amount of higher olefins, whereby a predetermined concentration of higher olefins is maintained in the catalyzing operation.

3. In the production of polymerized olefins wherein a heated gaseous mixture containing a substantial amount of normally gaseous higher olefins is passed at a temperature not substantially in excess of about 550° F. in contact with a catalyst and the product resulting from the catalyzing operation is subjected to fractional separation in a stabilizing chamber to form a liquid product and a composite normally gaseous product lean with respect to its content of higher olefins, the improvement which comprises withdrawing at least a portion consisting of a controlled quantity of the composite lean normally gaseous product and returning said portion to the catalyzing operation, the return of said portion being so regulated as to produce a predetermined concentration of higher olefins in the catalyzing operation.

JOSEPH G. ALTHER.
